UNITED STATES PATENT OFFICE.

ALDEN C. ROBINSON, OF ABERDEEN, WASHINGTON.

COMBINED CURTAIN AND SHADE BRACKET.

1,228,137.

Specification of Letters Patent. Patented May 29, 1917.

Application filed December 18, 1916. Serial No. 137,624.

To all whom it may concern:

Be it known that I, ALDEN C. ROBINSON, a citizen of the United States, residing at Aberdeen, in the county of Grays Harbor 5 and State of Washington, have invented a new and useful Combined Curtain and Shade Bracket, of which the following is a specification.

This invention relates to combined curtain and shade brackets, one of its objects 10 being to provide a simple, durable and efficient device which can be applied readily to a window casing without requiring the use of screws, nails or the like or mutilating the casing to an objectionable extent.

A further object is to provide a structure 15 of this character which can be adjusted to supports of different sizes and which, when not in use, can be easily removed without leaving a noticeable scar.

Another object is to provide a bracket which can be easily adjusted by the use 20 of ordinary tools and without requiring the services of a skilled mechanic.

With the foregoing and other objects in view which will appear as the description 25 proceeds, the invention resides in the combination and arrangement of parts and in the details of construction hereinafter described and claimed, it being understood that changes in the precise embodiment of the invention herein disclosed, can be made 30 within the scope of what is claimed, without departing from the spirit of the invention.

In the accompanying drawings the preferred form of the invention has been shown.

In said drawings:

40 Figure 1 is a front elevation of brackets embodying the present improvements, the curtain support carried thereby being broken away and that portion of the casing or support between the two brackets being removed.

Fig. 2 is a section on line 2—2 Fig. 1.

Fig. 3 is an elevation of the outer side of one of the brackets, the curtain support being removed.

50 Fig. 4 is a section on line 4—4 Fig. 1.

Fig. 5 is a section on line 5—5 Fig. 1.

Fig. 6 is a front elevation of a modified form of device.

55 Fig. 7 is a front elevation of another modification.

Referring to the figures by characters of

reference 1 and 2 designate upper and lower base strips each of which is provided with a longitudinal slot 3. These strips are bent along their longitudinal centers 60 so as to be preferably V-shaped in cross sectional contour and both strips are lapped by the end portions of a coupling strip 4 which fits snugly upon and straddles the strips and is adjustably attached to them 65 by screws 5 or the like extending through the slots 3 and engaging nuts or the like back of the strips and within the angle portions thereof as shown at 6 in Fig. 4. The coupling strip 4 is preferably attached to 70 the strips 1 and 2 at their inner ends or, in other words, at those ends thereof removed from the outer sides of the window casing or other support to which the brackets are attached. That end of the 75 strip 1 removed from the coupling strip 4 has an integral forwardly extending arm 7 on the free end portion of which is provided an upwardly extending lug 8. This arm has a slot 9 in the base portion thereof through which extends a clamping strip 10 one end of which is attached to the strip 1 by a screw 11 or the like engaging a nut 12 arranged back of the strip 1. The other end of the clamping strip projects through 80 the slot 9 and is bent backwardly to form a gripping finger 13 on the free end of which is provided a prong 16.

Arranged within the angle portion of the strip 2 so as to lie back of the said strip is 85 another clamping strip 17 preferably V-shaped in cross section and which has a longitudinal slot 18 for the reception of a screw 19 which extends through the slot 3 in the strip 2. Screw 19 engages a nut 20 back of the strip 17 and, when tightened, will hold the two strips 2 and 17 against movement relative to each other. The outer or free end portion of strip 17 has a gripping finger 21 at the free end of which is provided an inwardly extending tooth indicated by dotted lines at 22 in Fig. 1 and which tooth is adapted to bite into the outer side of the window casing or other supporting structure. That end of strip 2 nearest 100 the coupling strip 4 is also formed with a gripping finger 23 similar to the finger 21 and also formed with a tooth 24 adapted to bite into the adjacent surface of the window casing or other support. Straddling each 110 of the strips 1 is the base 25 of a shade supporting bracket 26, said base being held in

position on the strip 1 by a screw 27 engaging a nut 28 back of the strip 1.

It is to be understood that two of the structures herein described are to be provided, one being the direct opposite of the other so that they can be used upon opposite portions of a window casing or the like. In applying one of the structures to a window casing as shown in Fig. 1, the screws 11 and 19 are loosened and strips 2 and 17 are placed against the upper portion of the casing C and are then adjusted toward each other so that the teeth 22 and 24 will bite into opposed faces of the casing. Screw 19 is then tightened so that the parts will be held in position, after which the strip 10 is adjusted longitudinally to cause the prong 16 to bite into the adjacent side of the casing. Screw 11 is then tightened. The brackets 26 on the two structures are then adjusted relative to each other so that they will properly engage the trunnions at the ends of a shade roller. A curtain rod preferably made of telescoping tubes and a portion of which rod has been indicated at 29 is adjusted longitudinally and the ends of the rod which are flattened and extended parallel to each other are slipped onto the arm 7, as shown at 30 in Figs. 1 and 4.

Within the upper portions of the flattened ends are provided openings 31 and the lugs 8 are adapted to be seated within these openings. See Fig. 5.

Another form of the device has been illustrated in Fig. 6. This form is especially useful where the upper edge of the window casing is projected inwardly from the wall and presents a surface which can be engaged by the attachment. In this form, two adjustably connected strips 32 are provided, the same corresponding with the strips 2 and 17 hereinbefore described and having toothed fingers 33 at their free ends for engaging the opposed upper and lower faces of the top of the window casing C'. Extending from an intermediate portion of one of the strips 32 is a strip 34 having a longitudinal slot 35 in which is adjustably mounted a clamping strip 36 corresponding with the strip 10. This clamping strip extends through a forwardly extending arm 37 similar to the arm 7. A shade supporting bracket 38 is adjustably mounted on the strip 34.

Where a double window casing is used and it is desired to support two window shades, a modified form of bracket such as shown in Fig. 7 can be employed. This bracket includes lapping longitudinally slotted strips 39 similar to the strips 2 and 17 and provided at their outer ends with toothed fingers 40 adapted to engage opposed faces of the intermediate portion C' of the casing. These strips are adjustably connected as in the other structures de-

scribed. From the outer or free end portions of the strips 39 extend the coupling strips 41 the upper ends of which are adjustably secured by screws 42 or the like to a longitudinally slotted strip 43, said screws 70 extending through the slots 44 within the strip. Mounted on an intermediate portion of the strip 43 is a base 45 from which extend parallel arms 46 similar to the arms 7 and 37. These arms are adapted to engage 75 the inner end portions of two curtain supporting rods. Adjustably mounted on the strip 43 between the strips 41 and the arms 46 are bases 47 from which extend arms 48 for engaging the trunnions at the ends of 80 shade carrying rollers.

Obviously the various structures 45 and 48 can be adjusted relative to each other and to the strip 43 so that the structure will thus be adapted to window casings of different 85 sizes and to shade rollers and curtain rods of different lengths.

What is claimed is:—

1. The combination with adjustably connected lapped strips, having toothed support 90 engaging members extending from the outer ends of the strips, of a clamping strip adjustably connected to and extending at right angles from one of said lapping strips, a gripping finger extending from said clamping strip, and an outstanding curtain rod engaging member constituting a guide for the clamping strip.

2. The combination with adjustably connected strips having toothed gripping fingers extending therefrom, of a longitudinally slotted strip coupled to one of the first named strips, a curtain rod engaging arm outstanding therefrom and having an opening therein, a gripping finger adjustably connected to said slotted strip and projecting through and guided by the arm, and a shade roller supporting bracket adjustably mounted on said strip.

3. The combination with adjustably connected strips having toothed gripping fingers extending from the outer ends thereof, of a longitudinally slotted strip, a coupling strip adjustably connected to one of the first named strips and to said longitudinally 110 slotted strip, a gripping element adjustably connected to the longitudinally slotted strip, a shade roller supporting bracket adjustably mounted on said strip, an arm outstanding from the strip and constituting a 115 guide for the gripping element, and a curtain supporting rod having a slotted end detachably mounted on the arm, there being a stud upon the arm and an aperture in the rod within which the stud is detachably 120 seated.

4. The combination with lapping longitudinally slotted strips angular in cross sectional contour, means for securing said strips together, and toothed gripping fin- 130

gers at the outer ends of the strips, of a longitudinally slotted strip parallel with thelapping strips, and angular in cross sectional contour, a coupling strip straddling one of 5 the lapping strips and the longitudinally slotted strip and adjustably connected to them, an arm outstanding from the longitudinally-slotted strip and having an opening therein, a toothed gripping element extending 10 through the opening in said arm and adjustably connected to the longitudinally slotted strip, and a shade roller supporting bracket adjustably mounted on said strip.

15 5. The combination with opposed brackets

including gripping elements, and outstanding arms having upwardly projecting lugs thereon, of a curtain supporting rod having flattened ends extending at right angles therefrom and detachably mounted on the 20 arms, each of said ends having an opening in the upper portion thereof for the reception of the lugs.

In testimony that I claim the foregoing as my own, I have hereto affixed my signature 25 in the presence of two witnesses.

ALDEN C. ROBINSON.
